DESIGN FOR MERCHANTS' DISCOUNT STAMP OR SIMILAR ARTICLE

Jacob L. Ellman, University City, Mo.

Application December 6, 1937, Serial No. 73,386

Term of patent 3½ years

To all whom it may concern:

Be it known that I, Jacob L. Ellman, a citizen of the United States, residing at University City, Missouri, have invented a new, original, and ornamental Design for Merchants' Discount Stamp or Similar Article, of which the following is a specification, reference being had to the accompanying drawing, forming part thereof.

The drawing shows a face view of the stamp embodying my design. The stamp has no appreciable thickness.

I claim:

The ornamental design for merchants' discount stamp or similar article, substantially as shown.

JACOB L. ELLMAN.
